[57] **CLAIM**

The ornamental design for a winged catheter cover, as shown and described.

DESCRIPTION

FIG. 1 is a perspective view of a winged catheter cover showing our new design;

FIG. 2 is a front end elevational view thereof;

FIG. 3 is a rear end elevational view thereof;

FIG. 4 is a top plan view thereof;

FIG. 5 is a side elevational view thereof;

FIG. 6 is a bottom plan view thereof; and,

FIG. 7 is a perspective view thereof, the broken line showing of the catheter introducer needle assembly is for illustrative purposes only and forms no part of the claimed design.
